ROLL GRINDING MACHINE

Amos P. Steiner and Harold E. Balsiger, Waynesboro, Pa., assignors to Landis Tool Company, Waynesboro, Pa., a corporation of Pennsylvania.

Application August 29, 1929, Serial No. 389,279

4 Claims. (Cl. 51—49)

This invention relates to machines for grinding the surface of steel mill rolls and work of similar character and is designed for producing a crown or convex surface on the work. In carrying out the invention particular attention is paid to the means for grinding a convex curve to provide for deflection of the roll under a load or a concave curve which will compensate for expansion of the roll due to heat.

10. A further object is to provide means for taking up all lost motion between the driving elements and the roll and to eliminate back lash in the gearing of the crown and concaving mechanisms.

Referring to the accompanying drawings, which are made a part hereof and on which similar reference characters indicate similar parts,

Figure 1 is an end elevation of a machine on which our device is mounted with a section broken away to show the driving means of the several parts,

Figure 2 is an end elevation of the wheel base with parts broken away to show the gearing for the crowning and concaving mechanism and the wheel feed,

25. Figure 3 is a plan view of the wheel base with parts broken away to show the gearing shown in Figure 2,

Figure 4 is a rear view of the wheel base showing the toggle arms for moving the wheel base to produce the crown or concavity on the work,

Figure 5 is a sectional view of the crank shaft and a crank pin taken on line 5—5 of Figure 4.

Figure 6 is a section on line 6—6 of Fig. 3.

Figure 7 is a detail sectional view of a modified form of back lash eliminating means in which back lash is automatically taken up.

Figure 8 is an end view showing the flanged portion of a spindle for operating the wheel base oscillating mechanism.

10. Figure 9 is a section on line 9—9 of Figure 8.

Figure 10 is a diagrammatic sketch showing the method of developing the curves formed in grinding a convex or concave surface on a cylindrical work piece,

15. Figure 11 is a further diagrammatic view representing the surface of a crowned roll or concave roll in which the curve is developed from that plotted directly from the dial readings, as given in Fig. 10.

0. Figure 12 is a development of the driving means for the work carriage and that for operating the crowning mechanism, the view showing the relation between the parts but with the several parts out of their actual position to show the connection more clearly.

Figure 13 is a section on line 13—13 of Fig. 12, and

Figure 14 is a detail sectional view of one of the clutches.

Our invention consists primarily of mechanism for moving a grinding wheel of a roll grinding machine toward and from the work piece in such a way as to produce a regular crowned or concaved surface on the roll. Means are provided to reproduce the curve formed by a straight roll under load or to provide for the expansion of the roll as it becomes heated. In designing our device the deflection or expansion of the roll is predetermined and the mechanism designed to compensate for such deflection or expansion.

In the drawings numeral 10 indicates the bed of a roll grinding machine having a work carriage 11 upon which is mounted the work 12 here shown as a large roll, the work being held between head stocks and tail stocks of the usual construction, of which the latter alone is shown at 13. The work may be driven in any suitable way as by a motor 14 operating through suitable reduction gearing, not shown.

A grinding wheel 15 is mounted upon a wheel base 16 which is pivoted at 17 upon a sub-slide 18 which sub-slide is mounted upon the bed of the machine and may be moved toward and from the work 12. The grinding wheel is driven from a motor 19 through suitable belts not shown. The 20 grinding wheel base 16 may be moved upon the sub-slide by the following mechanism: A vertical shaft 19 has on its lower end a bevel gear 20 which meshes with a corresponding bevel gear 21 on a screw 22. A horizontal shaft enclosed in 25 a casing 23 has a bevel gear meshing with a bevel gear on the upper end of the shaft 19, not shown. A hand wheel 24 provides manual means for rotating the shaft 19 to move the wheel base toward and from the grinding wheel. Power means for 30 moving the grinding wheel toward and from the work comprises a motor 25 and speed reducing means shown as a whole at 26, by means of which the shaft 19 is rotated to move the grinding wheel toward and from the work. The wheel 35 feed mechanism just described is similar in most respects to that in well-known grinding machines and will not be further described here.

Means for swinging the wheel base on its pivot 17 will now be described. This consists of a 50 pair of spindles 27 and 28 each having on its outer end a flange 29. This flange has an annular slot 30 (Figs. 5, 8, 9). Crank pins 31 and 36 are secured to the flanged portions by means of bolts 32. The heads of the bolts engage in the 55

slot 30 so that the crank pins may be rotated about the flanges on the shafts 27 or 28. The bolts 32 pass through a flanged portion 33 on the end of the crank pins 31 and 36. These latter flanged portions have suitable graduations as shown at 34. The reasons for the graduations and the adjustability of the flange portions 33 with respect to the flange 29 will later appear.

Toggle arms 37 and 38 are mounted on the 10 crank pins 31 and 36 respectively. The upper ends of these toggle arms are pivotally connected to a pin 39 on which is mounted a roller 40. The roller 40 engages beneath the outer end of a bracket 41 mounted on the top of the wheel 15 base 16.

From the construction just described it will be seen that rotation of the shafts 27 and 28 will rock the wheel base 16 on its pivot 17.

The spindles 27 and 28 are driven from the 20 same drive as the work carriage is driven. The driving mechanism is as follows: The shaft 42 is directly driven by a suitable motor. A pinion 43 on this shaft drives a pinion 44 on a shaft 45. A pinion 46 on shaft 45 drives a gear 47 loosely 25 mounted on a shaft 79. A hub 80 made integral with the gear 47 has gear teeth cut therein which mesh with a gear 81 loosely mounted on a shaft 82. The shaft 82 has a pinion 83 on one end which drives a rack 84 on the work carriage 11. The 30 pinion has clutch teeth 85 on one side which are engaged by lugs 86 on the shaft 82. A certain predetermined clearance is provided between the lugs 86 and the clutch teeth 85. Loosely mounted on the shaft 82 is a gear 87 which meshes with a gear 88 on the shaft 79. The gear 88 has a 35 hub gear 89 which meshes with a gear 90 keyed to the shaft 82. The gear 90 drives a gear 91 on the shaft 48. The gear 81 has clutch teeth 92 which mesh with clutch teeth 93 on the gear 87. 40 when the gear 81 is moved against the gear 87. The work carriage may be driven through gears 43, 44, 46, 47, 80, 81, clutches 94, 86, 85, pinion 83 to rack 84, or when the gear is moved axially to the right the drive is through gears 80, 81, 45 clutches 92, 93, gears 87, 88, 89, 90, shaft 82, clutch lug 86, clutch teeth 85, pinion 83 to rack 84. The latter provides a slow speed drive for the work carriage. A clearance is provided at 95 between the lugs 86 on the shaft 82 and the 50 teeth 85 on the pinion 83, so as to provide a lost motion between the driving gears described and the rack 84. This clearance is made to take care of the lost motion between the pinion 80 and the shaft 59 later to be described, so that 55 the pinion 83 will start movement of the rack 84 just as the shaft 59 begins to rotate. The clearance 95 therefore compensates for lost motion between gear 80 and worm shaft 59. The shaft 49 is driven by means of pinion 50 on shaft 60 48, pinion 52 on shaft 49 and an intermediate pinion 51. The relative sizes of the pinions 50, 51 and 52 determine the relative speeds of the shafts 48 and 49. These pinions may be removed and pinions of other sizes substituted to vary the 65 speed of the shaft 49. The shaft 49 has a bevel gear 53 keyed thereto and slidably mounted thereon. The gear 53 meshes with a bevel gear 54 on a shaft 55 mounted in a bracket 56 which is secured to the lower side of the sub-slide 18. 70 The shaft 55 has a bevel gear 57 on its upper end which meshes with a bevel gear 58 on a shaft 59. This shaft has worms 60 and 61 thereon which mesh with worm wheels 62 and 63 on the shafts 27 and 28 respectively. Shafts 27 and 75 28 have also gears 64 and 65 each of which meshes

with an idle gear 66. From the construction just described it will be seen that as the work carriage 11 is reciprocated the spindles 27 and 28 are rotated and that reversing the work carriage 11 reverses the rotation of the spindles. In order that the crowned or concaved surface of the roll may be accurate it is necessary to eliminate all lost motion between the driving mechanism connected to the work carriage and the driven spindles 27 and 28. Means for doing this is shown 10 in detail in Figures 6 and 7, Figure 6 showing manual means for taking up back-lash and Figure 7 showing automatic means for accomplishing the same purpose. The hub of the gear 65 is provided with sockets for receiving set screws 15 67 and 68 which screws seat in sockets 69 and 70 cut in the spindle 28. Lost motion may be taken up by loosening screw 68 and tightening screw 67. By turning down screw 67 and loosening screw 68 a relative movement between the gear 65 and the 20 shaft 28 is produced, this gear tending to rotate in a clockwise direction as viewed in Figure 6 and the shaft 28 in a counterclockwise direction. The counterclockwise rotation of the shaft 28 turns worm gear 63 to take up back lash between said 25 gear and the worm 61. When said worm is driving said worm gear is moved in a clockwise direction, that is, in a direction to rotate shaft 28 in a clockwise direction as viewed in Fig. 6. The tendency of gear 65 to rotate in a clockwise direction turns the gear 66 in a counterclockwise direction which rotates the gear 64 in a clockwise direction. The gear 64 in turn rotates the shaft 27 in a clockwise direction, as shown in Figure 6, to rotate the worm gear 62 to take up back lash 30 between this gear and the worm 60.

It will be seen that adjusting screw 67 causes worm wheels 62 and 63 to rotate in opposite directions, thus tending to move the worms 60 and 61 toward each other so that when said shaft 40 59 turns in a given direction one worm drives the toggle arms through one of the shafts and when it rotates in the other direction the other worm drives the other shaft to drive the toggle arms. In other words the driving connection 45 between the traverse carriage and the toggle arms is always through one of the shafts 27 or 28 while the other idles. When the work carriage moves in the opposite direction the driving is through the other shaft so that the driving connection is always through one shaft while the other idles. Since the back lash is taken up in both directions all lost motion will be eliminated between the 55 driving mechanism and the driven mechanism which is the toggle arms which operate to swing the wheel toward and from the work.

In Figure 7 is shown automatic mechanism for taking up lost motion. In this case the hub of the wheel 65 is provided with a bushing 71 and a set screw 72 is screwed into the bushing so that its end rests against the bottom of a socket 73 in the shaft 28. The outer end of the bushing is enlarged to receive a spring 74, one end of which is secured in the bushing and the other end in a 60 collar 75. The collar is secured to the screw 72 by means of a set screw 76. The spring 74 is tensioned by rotating the collar 75 and securing it in position by means of set screw 76. A small clearance is allowed between the collar 75 and the 65 top of the bushing 71 and the spring 74 tends to rotate the screw 72 to keep its end tightly against the bottom of the socket 73. It will be seen therefore that the tendency of the spring 74 is always to rotate the screw 72 to rotate the 70

gear 65 in a clockwise direction and to rotate the shaft 28 in a counterclockwise direction. The gear 65 and shaft 28 will both rotate until they have eliminated all lost motion between the worm gears 62 and 63 and the corresponding worms 60 and 61 on the shaft 59 as described above with respect to the device as shown in Fig. 6.

A screw 76 operated by a lever 77 is threaded through the top of the wheel base and may be screwed down to have its lower end rest upon a plate 78 secured to a portion of the sub-slide. The purpose of this screw is to remove the weight of the wheel base from the rolls 40.

The operation of the machine is as follows: The grinding operation should begin with the grinding wheel at the center of the work piece to be crowned or concaved. The weight of the wheel base 16 is removed from the roller 40 by the screw 76. The crank pins 31 and 36 are then rotated by shifting the dials 32 until the markings thereon are moved the desired distance from a zero mark which indicates a certain crown or concavity which has been predetermined. The left-hand crank pin 31, as seen in Fig. 4, will be rotated counterclockwise and the right hand crank pin rotated clockwise to get the correct starting position for crowning. For concaving the dials are shifted in the opposite direction. The dials are preferably graduated in degrees and by means of a chart the operator may determine the correct setting for a given roll. The spindles 27 and 28 carrying crank pins 31 and 36 are rotated by gearing connection from the mechanism which drives the work carriage as has been described. Movement of the carriage in one direction rotates the shafts 27 and 28 in one direction and reversing the carriage reverses the rotation of these shafts. As the shafts tend to rotate they lift the wheel base 16 to rock it on its pivot 17. The rocking of the wheel base and the movement of the work carriage are so timed that the correct crown or correct concavity is ground by the grinding wheel.

In Figures 10 and 11 the operation of the device is shown somewhat diagrammatically. In these figures the zero or straight line setting of the dials is shown by arrows in Figure 10 at a point 30 degrees above the horizontal in a clockwise direction for dial X and in a counterclockwise direction for dial Y. Shifting the dials so as to bring the zero mark above the straight line setting establishes a setting for grinding a concave roll. The setting for grinding a crowning surface is obtained by shifting the dials to bring the zero mark below the straight line setting. As further shown in Figure 10, the figures indicate the development of the crowning surface and the letters the concaving surface. The two curves shown in the drawings in Figure 11 are drawn out to represent the surfaces of a crowned roll and a concaved roll, the points being transferred from those plotted directly from the dial readings. These two views are rather diagrammatic but serve to show how the curves are developed and further show that an adjustable throw crank shaft or eccentric is not necessary for grinding crowned or concaved surfaces of a roll. Of course in operation the crank pins rotate at the same speed and in the same direction. It should be noted that the worm 61 drives the worm wheel 63 and the worm 60 drives the worm wheel 62. The driving, therefore, is always through only one of the worms at a time, the teeth of the other worm being meshed opposite so that the worm wheel idles. For instance if the worm 61

is driving the worm wheel 63, the shaft 28 will be driven in a counterclockwise direction as shown in Figure 6. Power is also delivered through gear 65, idle gear 66 to gear 64 and the shaft 27 to rotate this shaft likewise in a counterclockwise direction to operate the crank pins 31 and 36 and swing the toggle arms to tilt the wheel base 16 toward and away from the work. While the carriage is moved in this direction the worm 62 is doing no work, however, as soon as the carriage 10 is reversed the worm 60 takes up the load and drives the shaft 27 through the worm wheel 62 and the motion is repeated in the opposite direction with the worm 63 idling. Reversing of the work carriage therefore causes an instant driving of the toggle links which swing the wheel base on its pivot. In crowning, the dials and hence the crank pins are positioned as described above. Assuming that the carriage moves first to the right the grinding wheel being at the center of the roll the crank pins rotate in a clockwise direction lifting the roll and tilting the wheel 14 toward the work until the end of the roll is reached and the carriage and crowning mechanism are reversed. The wheel then tilts away from the work until it passes the center at which point it is furthest from the axis of the work piece and then moves toward the work until the other end of the roll is reached. In concaving the wheel tilts away from the work as it moves from the center toward the end.

It will be obvious to those skilled in the art that various changes may be made in our device without departing from the spirit of the invention and therefore we do not limit ourselves to what is shown in the drawings and described in the specification, but only as indicated in the appended claims.

Having thus fully described our said invention, what we claim as new and desire to secure by Letters Patent, is:

1. In a machine of the kind described, a work support, a wheel support, means to provide relative transverse and longitudinal movement between said supports, means to effect said movements simultaneously comprising a system of gears to effect said transverse movement, another system of gears to effect said longitudinal movement, common driving means for both systems, and means to provide lost motion at the end of one system to correspond to the difference in back lash in the two systems.

2. In a machine of the kind described, a work support, a tool support, means to effect relative transverse and longitudinal movement between said supports, means to initiate said movements simultaneously comprising mechanism to effect said transverse movement, another mechanism to effect said longitudinal movement, common driving means for both mechanisms, and means to provide lost motion in one mechanism to correspond to the difference in back lash in the two mechanisms.

3. In a machine of the kind described, a work support, a tool support, a crowning and concaving mechanism for causing a relative movement between said supports in a direction substantially perpendicular to the work surface comprising a pair of shafts, each shaft having a gear mounted thereon eccentric elements on each of said shafts and adapted to rotate therewith, means engaging one of said supports and adapted to be actuated by both said eccentric elements to effect said relative movements, means to rotate said eccentric elements in synchronism comprising

- an adjusting screw mounted in one of said gears and adapted to bear against a portion of the shaft to effect rotation between said gear and said shaft and automatic means to maintain said screw in contact with said shaft.
4. In a machine of the kind described a bed, a work support and a tool support mounted thereon, a crowning and concaving mechanism for causing a relative movement between said supports in a direction substantially perpendicular to the work surface comprising a pair of shafts extending outside the bed, driving means for said

shafts, means to rotate said shafts synchronously, flanged portions on the extended end of each shaft, discs adjustably secured to each of said flanged portions, each of said discs having a pin eccentrically positioned thereon and on the opposite side of the disc from the shaft, means engaging one of said supports and adapted to be actuated by both said pins to effect said relative movement.

HAROLD E. BALSIGER. 10
AMOS P. STEINER.
